CLAIM

An ornamental design for an animal waterer, as shown and described.

DESCRIPTION

FIG. 1 is a perspective view of the first embodiment of the animal waterer according to the invention.

FIG. 2 is a front view of the first embodiment of the animal waterer according to the invention.

FIG. 3 is a rear view of the first embodiment of the animal waterer according to the invention.

FIG. 4 is a side view of the first embodiment of the animal waterer according to the invention.

FIG. 5 is a top view of the first embodiment of the animal waterer according to the invention.

FIG. 6 is a bottom view of the first embodiment of the animal waterer according to the invention.

FIG. 7 is a perspective view of the second embodiment of the animal waterer according to the invention.

FIG. 8 is a front view of the second embodiment of the animal waterer according to the invention.

FIG. 9 is a rear view of the second embodiment of the animal waterer according to the invention.

FIG. 10 is a side view of the second embodiment of the animal waterer according to the invention.

FIG. 11 is a top view of the second embodiment of the animal waterer according to the invention; and,

FIG. 12 is a bottom view of the second embodiment of the animal waterer according to the invention.
